[57] CLAIM

The ornamental design for a lower left quadrant of a watch housing, as shown and described.

DESCRIPTION

FIG. 1 is a top view of a lower left quadrant of a watch housing in accordance with our invention;

FIG. 2 is a left side elevation view of the lower left quadrant of FIG. 1;

FIG. 3 is a bottom view of the lower left quadrant of FIG. 1;

FIG. 4 is a front view of the lower left quadrant of FIG. 1; FIG. 5 is a top view of a second embodiment of a lower left quadrant of a watch housing in accordance with our invention;

FIG. 6 is a left side elevation view of the lower left quadrant of FIG. 5;

FIG. 7 is a bottom view of the lower left quadrant of FIG. 5;

FIG. 8 is a front view of the lower left quadrant of FIG. 5; FIG. 9 is a top view of a third embodiment of a lower left quadrant of a watch housing in accordance with our invention;

FIG. 10 is a left side elevation view of the lower left quadrant of FIG. 9;

FIG. 11 is a bottom view of the lower left quadrant of FIG. 9; and,

FIG. 12 is a front view of the lower left quadrant of FIG. 9. The broken lines show the remainder of the watch housing, including buttons and a display, and watch bands for illustrative purposes only and form no part of the claimed design.
